UNITED STATES PATENT OFFICE.

JAMES G. JOHNSTON, JR., OF CHICAGO, ILLINOIS, ASSIGNOR TO WARREN FEATHER-BONE COMPANY, OF THREE OAKS, MICHIGAN, A CORPORATION OF MICHIGAN.

DISPLAY STAND FOR BELTING AND LIKE MATERIAL.

Application filed April 8, 1921. Serial No. 459,579.

To all whom it may concern:

Be it known that I, JAMES G. JOHNSTON, Jr., a citizen of the United States, and a resident of Chicago, in the county of Cook and State of Illinois, have invented certain new and useful Improvements in Display Stands for Belting and like Material, of which the following is a specification.

This invention relates to improvements in display stands for certain kinds of dry goods, such as belting or like materials, ordinarily retailed in yard lengths, multiples or fractions thereof. The type of stand embodying the novel features of construction is one designed to be placed upon a counter, and to hold a number of bolts of the material in the various widths, quality or color. The several bolts are wound on rotative spindles, from which the desired lengths of the material are unwound and severed as the sales are made. As the bolts are disposed of, new ones are placed upon the spindles.

The difficulties ordinarily experienced in the use of these stands, and particularly of freely rotative and removable spindles are, first, the undesired unwinding of the bolts of material, caused by the weight of the depending free end thereof; and second, the loss of spindles due to the thoughtlessness of sales persons in discarding the empty spindles when a bolt is exhausted, under the erroneous belief that a spindle accompanies each bolt of material. This being not usually the case, the spindles are being constantly lost, and as a result, demands on the manufacturer for new spindles are continual.

The object of the invention is to provide a simple, yet effective expedient which will eliminate the objections mentioned, by providing a combined friction brake acting on the spindle, and a flexible connection between the spindle and the stand. The function and mode of operation of the device will hereinafter be more fully disclosed in connection with the accompanying drawing, in which—

Figure 1 is a view in front elevation of the complete stand,

Figure 2 is an enlarged view in front elevation of a single spindle unit, showing the improved construction,

Figure 3 is a detailed view in vertical section taken on line 3—3 of Figure 2, and

Figure 4 is a detailed view in vertical

section of the drum taken on line 4—4 of 55 Figure 2.

The stand is an open structure preferably made of wood, and consisting of a base 1, upon which is erected a vertical frame made of a plurality of parallel uprights 2, and a horizontal top member 3. The uprights are spaced apart at various distances, thereby forming a series of compartments for different widths of the material. In each compartment are mounted one or more rotative 60 spindles 4, there being illustrated two of such spindles, one above the other.

Considering one of the spindles, and an adjacent portion of each compartment consisting of two upright 2—2, Figures 2 and 70 3, the spindle 4 consists of an elongated block tapering to an edge at its ends, and provided with journal pins 5—5 arranged to coincide with the minor or horizontal axis of the block. In the lateral faces of 75 the uprights are cut L-shaped slots 6—6, extending inwardly and downwardly from the forward edge thereof, the lower extremities forming U-shaped bearings for the journal pins. As thus constructed, it is manifest 80 that the spindles are made to rotate freely within the bearing slots, and are capable of being readily removed therefrom. This freedom of rotative movement and bodily removal is, however, limited by the addition 85 of the following parts: Mounted upon, or forming part of one of the journal pins 5 of each spindle, is a drum 7 consisting of a central portion 8 included between flanges 9—9 of slightly greater diameter. The central portion 8 of the drum is formed with two diametrically opposed flattened surfaces 8^a—8^a, Figure 4, the distance between them being less than the normal diameter of said central portion. Surrounding the drum 7 90 and engaging the central portion 8 thereof, is a yieldable member 10, consisting of two spring arms 10^a—10^a fitting snugly around the drum, and overlapping each other at their free ends. The opposite ends of the 95 arms are united in a coil 10^b, whereby the desired degree of tension is introduced into the member 10. Connecting the yieldable member 10 with the frame, and directly with the adjacent upright 2, is a flexible chain preferably made up of several long links 11 joined together in the usual manner, the connected end being fastened to the upright

2
in any suitable manner, and preferably at a point near the front edge and a short distance below the bearing slots of the journal pins as at 12. The type of chain shown is 5 preferred to one made of shorter links, and therefore more flexible. The reason is, that there is less tendency for the less flexible links becoming twisted and shortened in the removing and replacing the spindle in the 10 act of renewing the bolts of material.

The yieldable member 10 acts as a brake in the sense that it exerts sufficient tension on the drum to prevent the weight of the unwound end portion of a belt from rotating 15 the spindle. The braking action is intermittent rather than constant; that is, a frictional resistance is offered to the rotation of the spindle by the spring arms, during a portion of each revolution thereof, this being 20 ample to prevent the unwinding of the material. Furthermore, the yieldable member and the several links 11 prevent the spindle being completely detached from the stand, altho it does permit its removal for the purpose of inserting a new bolt of material upon 25 the spindle.

Having described the structure embodying the invention, I claim:

1. In a device of the character described, 30 the combination of a frame, a spindle journaled in said frame and capable of removal therefrom, and a yieldable member surrounding a grooved portion of said spindle,

and connected with said frame, thereby acting to exert frictional resistance to the free 35 rotation of said spindle, and for connecting the same to said frame.

2. In a device of the character described, the combination of a frame comprising horizontally spaced uprights, a spindle journaled in slots formed in said uprights, a yieldable member comprising spring arms surrounding an annular portion of said spindle, and flexibly connected with said 40 frame. 45

3. In a device of the character described, the combination of a frame, a spindle rotatively journaled in said frame, and comprising a drum axially disposed, and a yieldable member comprising spring arms encircling said drum, and adapted to exert an intermittently applied frictional resistance to the free rotation of said spindle. 50

4. In a device of the character described, the combination of a frame, a spindle rotatively journaled in said frame, and comprising an axially disposed drum having a flattened surface, a brake member comprising spring arms encircling said drum, and adapted to exert an intermittently applied frictional resistance to the free rotation of said spindle, and a plurality of links connecting said brake member to said frame. 55

In witness whereof, I hereunto subscribe my name this 2nd day of April, A. D., 1921.

JAMES G. JOHNSTON, JR.
